UNITED STATES PATENT OFFICE

CHARLES MORRISON YOUNG, OF NELSON, BRITISH COLUMBIA, CANADA

NET

Application filed January 7, 1930. Serial No. 419,102.

This invention relates to improvements in nets, and particularly landing nets for fishing, but is also applicable to butterfly nets, grasshopper nets and the like.

5 An object of the invention is to provide a simple and efficient folding net of this character.

A further object of the invention is to provide a folding net in which the metal supporting frame of the net will assume the desired shape without auxiliary shaping attachments.

10 A further object of the invention is to provide a net of this character in which the net frame is very durable, particularly at the points of greatest strain.

15 A further object of the invention is to provide a simple form of folding net which may be manufactured at low cost.

20 With these and other objects in view, the invention consists essentially of a net frame formed in two flexible sections hingedly connected together with the provision of two folding handle members in pivotal and folding connection with the pivotal supports of the net frame, as more fully described in the present specification and illustrated in the accompanying drawings which form part of the same.

25 In the drawings:

Figure 1 is a plan view of the net in open position.

Figure 2 is a plan view of the same in folded position.

30 Figure 3 is a side elevation of Figure 1.

Figure 4 is an enlarged section on the line 4—4 of Figure 3.

Figure 5 is a perspective detail of one of the hinge members or boxings connected with the handles and the net supporting frame.

Figure 6 is a plan view of the blank used for the boxings, and

Figure 7 is a plan view of one of the net supports.

35 Referring more particularly to the drawings, A indicates the device as a whole comprising the handle members 10 and 11 and the net supporting frame B including the supporting members 13 and 14. The supporting members are made of flexible material,

being tapered towards their outer end as at 15 and provided with ears 16 or otherwise formed and provided with an orifice 17.

40 A split ring or the like 18 is designed to extend into the orifice 17 to retain the parts 13 and 14 together at one end and the inner ends of the supporting members 13 and 14 are suitably orificed as at 19 to be riveted or otherwise secured to the hinge members or pivotal boxings 20.

45 The pivotal boxings are preferably substantially sector shaped, comprising the upper and lower walls 21 and 22, the side wall 23 and the opposite side wall composed of bent extensions of the upper and lower walls 21 and 22 as indicated in Figure 5 at 24. This structure of boxing may, of course, be altered according to requirements but this form is preferable, being made up from the blank as illustrated in Fig. 6.

50 The upper and lower walls 21 and 22 are provided with lugs 25 which are orificed at 26 to receive therethrough a pin 27 to hingedly connect two of these hinge members as used in the complete construction. A further pair of orifices 28 are provided in the upper and lower walls 21 and 22 to receive therethrough the pins 29 which pivotally connect the handles 10 and 11 to these hinge members or boxings and with the riveting of the inner 55 ends of the supporting members 13 and 14 to the extensions 24 forming one of the side walls of these boxings, the structure is complete.

55 In this complete structure, it will be seen that the handles 10 and 11 pivoted to the walls 21 and 22 of the boxings may swing to abut either the side wall 23 or a side wall made up of extensions 24 and that they will correspondingly actuate the supporting members 13 and 14 in accordance with which side wall they engage.

60 In operation, assuming the net to be in the position shown in Figure 1, if it is desired to close this net the handles may be swung about their pivots 29 in the direction of the arrows, that is away from one another so that they immediately abut the side walls made up of the extensions 24 and on further operation the hinge members 20 swing about their pivot 65 100

or hinging point 27 so that outward pressure hitherto exerted on the supporting members 13 and 14 is eliminated and the supporting members 13 and 14 gradually assume a straightened position and finally are confined between the handles 10 and 11 as illustrated

in Fig. 2 in completely collapsed position.

On the other hand, it is only necessary to repeat this operation to open the net and on 10 swinging the handles 10 and 11 away from one another, they correspondingly swing on their pivots and engage with the side walls 23 of the boxings so that on further pressure being exerted on the handles the boxings 15 swing on their pivots and the side walls formed from the extensions 24 exert pressure on the supporting members 13 and 14, thus bending them into position shown in Fig. 1, the ring 18 of course in each case readily 20 permitting this movement and retaining the supporting members at the outer end.

It will be noted from the drawings that the supporting members when in opened normal position assume a substantially ovoid 25 shape in combination, which is the most desirable form for a net of this character and due to the fact that the supporting members 13 and 14 are tapered towards their outer ends, extreme flexibility will exist at the outer 30 ends, permitting the rounded form when the supports are in normal position, while the inner ends are of such character as to form a strong rigid support at the point where the most strain is encountered, i. e. at the joining 35 of the supports with the handle.

It will be of course understood that the supporting members are made up preferably of flexible spring steel and it may be readily seen that a structure of this character is very 40 efficient and may be manufactured without great difficulty and at comparatively low cost.

Various modifications may be made in this invention without departing from the spirit thereof or the scope of the claims, and therefore 45 the exact forms shown are to be taken as illustrative only and not in a limiting sense, and it is desired that only such limitations shall be placed thereon as are disclosed in the prior art or are set forth in the accompanying 50 claims.

What I claim as my invention is:

1. A folding net of the character described comprising hinge members pivotally secured together, a pair of tapered net supporting 55 members rigidly secured at their enlarged ends to hinge members and loosely connected together at their smaller ends, handle members pivotally secured to the hinge members and independently movable with respect 60 thereto, and bearing faces formed on said hinge members adapted to limit the independent movement of the handles whereby on oppositely swinging the handles the net may be opened or folded through contact of the handles with the bearing surfaces.

2. In a net structure of the character described including net supporting members and handles, hinge members comprising a casing formed with enclosed walls and an opening along one side thereof, said casings 70 being pivotally connected together and adapt-

ed to rigidly retain said supporting members and pivotally retain said handles.

In witness whereof I have hereunto set my hand.

CHARLES MORRISON YOUNG.
